CLAIM

The ornamental design for a toilet bowl, as shown and described.

DESCRIPTION

FIG. 1 is a perspective view of a toilet bowl showing our new design;

FIG. 2 is a front view thereof: the rear view being a mirror image thereof;

FIG. 3 is a top view thereof;

FIG. 4 is a bottom view thereof;

FIG. 5 is a right side view thereof, the left side view being a mirror image thereof;

FIG. 6 is 6-6 cross section view thereof; and,

FIG. 7 is 7-7 cross section view thereof.

In the drawings, the broken lines depict environmental subject matter only and form no part of the claimed design.
